UNITED STATES PATENT OFFICE.

FREDERICK WINK, OF PHILADELPHIA, PENNSYLVANIA, ASSIGNOR TO
THOMAS DOLAN, OF SAME PLACE.

DESIGN FOR SHAWL-PATTERN.

Specification forming part of Design No. 6,082, dated August 20, 1872.

Specification describing a Design for a
Shawl - Pattern, invented by FREDERICK
WINK, of Philadelphia, Pennsylvania.

Design for a Shawl-Pattern.

The principal features of the design, which is clearly shown in the accompanying drawing, are the stripes A and B and the intervening narrow stripe D. Each stripe A and B is composed of a series of minor stripes or ribs of varying widths, the central and exterior ribs *a* and *b* of the stripe A being ornamented by short transverse lines, as shown, while the central rib *d* of the stripe B is ornamented by a checkered pattern, too clearly shown in the drawing to need description. The ornamenta-

tion of the stripes D is similar to that of the central rib *d* of the stripe B.

Irrespective of the colors employed, I claim—

1. The design for the stripe A, substantially as described and represented.
2. The design for the stripe B, substantially as shown and described.
3. The design for the whole pattern, including the stripes A, B, and D.

In testimony whereof I have signed my name to this specification in the presence of two subscribing witnesses.

FRED. WINK.
